FISHING POLE HANDLE

James H. Hopper, 1 Taylor Road, Hazardville, Conn.

Filed Oct. 21, 1965, Ser. No. 87,683

Term of patent 7 years

(Cl. D31—4)

FIGURE 1 is a side view of the fishing pole handle according to my invention showing in dot-dash outline a reel on the handle and a portion of a fishing pole attached to the handle, for purposes of illustration only.

FIGURE 2 is a plan view looking down on top of FIG. 1.

FIGURE 3 is a fragmentary bottom plan view looking up from beneath FIG. 1.

FIGURE 4 is an end view looking in from the left side of FIG. 1.

FIGURE 5 is an end view looking in from the right side of FIG. 1.

I claim:

The ornamental design for a fishing pole handle, substantially as shown and described.
